ELECTRICAL TRANSMISSION TOWER

Arthur L. Scott, Columbia, S.C., assignor to C/P Corporation, Newberry, S.C., a corporation of South Carolina

Filed Oct. 4, 1968, Ser. No. 13,834

Term of patent 14 years

Int. Cl. D13—03

U.S. Cl. D26—12

FIG. 1 is a perspective view of the electrical transmission tower embodying my new design;

FIG. 2 is a front view thereof on an enlarged scale; and

FIG. 3 is a side elevational view thereof on an enlarged scale.

The broken line showing of insulators and ground area is for illustrative purposes only.

I claim:

The ornamental design for an electrical transmission tower, as shown and described.
